(57) **CLAIM**

The ornamental design for a combined electric toothbrush set, as shown and described.

DESCRIPTION

FIG. 1 is a front, right and top perspective view of component 1 of the combined electric toothbrush set showing my new design;

FIG. 2 is a rear, left and bottom perspective view thereof;

FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom plan view thereof;
FIG. 9 is a front, right and top perspective view of component 2 of the combined electric toothbrush set;
FIG. 10 is a rear, left and bottom perspective view thereof;
FIG. 11 is a front view thereof;
FIG. 12 is rear view thereof;
FIG. 13 is a left side view thereof;
FIG. 14 is a right side view thereof;
FIG. 15 is a top plan view thereof;
FIG. 16 is a bottom plan view thereof;
FIG. 17 is a front, right and top perspective view of component 1 and component 2 of the combined electric toothbrush set in a combined state;
FIG. 18 is a front, right and top perspective view of component 3 of the combined electric toothbrush set;
FIG. 19 is a rear, left and bottom perspective view thereof;
FIG. 20 is a front view thereof;
FIG. 21 is rear view thereof;
FIG. 22 is a left side view thereof;
FIG. 23 is a right side view thereof;
FIG. 24 is a top plan view thereof;
FIG. 25 is a bottom plan view thereof;
FIG. 26 is a front, right and top perspective view of component 1 and component 3 of the combined electric toothbrush set in a combined state;
FIG. 27 is a front, right and top perspective view of component 4 of the combined electric toothbrush set;
FIG. 28 is a rear, left and bottom perspective view thereof;
FIG. 29 is a front view thereof;
FIG. 30 is rear view thereof;
FIG. 31 is a left side view thereof;
FIG. 32 is a right side view thereof;
FIG. 33 is a top plan view thereof;
FIG. 34 is a bottom plan view thereof;
FIG. 35 is a front, right and top perspective view of component 1 and component 4 of the combined electric toothbrush set in a combined state;

(Continued)

FIG. 36 is a front, right and top perspective view of component 5 of the combined electric toothbrush set;
 FIG. 37 is a rear, left and bottom perspective view thereof;
 FIG. 38 is a front view thereof;
 FIG. 39 is rear view thereof;
 FIG. 40 is a left side view thereof;
 FIG. 41 is a right side view thereof;
 FIG. 42 is a top plan view thereof;
 FIG. 43 is a bottom plan view thereof;
 FIG. 44 is a front, right and top perspective view of component 1 and component 5 of the combined electric toothbrush set in a combined state;
 FIG. 45 is a front, right and top perspective view of component 6 of the combined electric toothbrush set;
 FIG. 46 is a rear, left and bottom perspective view thereof;
 FIG. 47 is a front view thereof;
 FIG. 48 is rear view thereof;
 FIG. 49 is a left side view thereof;
 FIG. 50 is a right side view thereof;
 FIG. 51 is a top plan view thereof;
 FIG. 52 is a bottom plan view thereof;
 FIG. 53 is a front, right and top perspective view of component 1 and component 6 of the combined electric toothbrush set in a combined state;
 FIG. 54 is a front, right and top perspective view of component 7 of the combined electric toothbrush set;
 FIG. 55 is a rear, left and bottom perspective view thereof;
 FIG. 56 is a front view thereof;
 FIG. 57 is rear view thereof;
 FIG. 58 is a left side view thereof;
 FIG. 59 is a right side view thereof;
 FIG. 60 is a top plan view thereof;
 FIG. 61 is a bottom plan view thereof;
 FIG. 62 is a front, right and top perspective view of component 1 and component 7 of the combined electric toothbrush set in a combined state;
 FIG. 63 is a front, right and top perspective view of component 8 of the combined electric toothbrush set;
 FIG. 64 is a rear, left and bottom perspective view thereof;
 FIG. 65 is a front view thereof;
 FIG. 66 is rear view thereof;
 FIG. 67 is a left side view thereof;
 FIG. 68 is a right side view thereof;
 FIG. 69 is a top plan view thereof;
 FIG. 70 is a bottom plan view thereof;

FIG. 71 is a front, right and top perspective view of component 1 and component 8 of the combined electric toothbrush set in a combined state;
 FIG. 72 is a front, right and top perspective view of component 9 of the combined electric toothbrush set;
 FIG. 73 is a rear, left and bottom perspective view thereof;
 FIG. 74 is a front view thereof;
 FIG. 75 is rear view thereof;
 FIG. 76 is a left side view thereof;
 FIG. 77 is a right side view thereof;
 FIG. 78 is a top plan view thereof;
 FIG. 79 is a bottom plan view thereof; and,
 FIG. 80 is a front, right and top perspective view of component 1 and component 9 of the combined electric toothbrush set in a combined state.
